UNITED STATES PATENT OFFICE.

HARRY R. CANFIELD, OF CLEVELAND, OHIO, ASSIGNOR TO THE ELECTRIC CONTROLLER & MANUFACTURING COMPANY, OF CLEVELAND, OHIO, A CORPORATION OF OHIO.

METHOD AND MEANS FOR CONTROLLING ELECTRIC CIRCUITS.

1,344,260.

Specification of Letters Patent. Patented June 22, 1920.

Continuation of applications Serial No. 583,000, filed September 21, 1910, and Serial No. 604,331, filed January 24, 1911. This application filed March 6, 1920. Serial No. 363,868.

To all whom it may concern:

Be it known that I, HARRY R. CANFIELD, a citizen of the United States, residing at Cleveland, in the county of Cuyahoga and State of Ohio, have invented new and useful Improvements in Methods and Means for Controlling Electric Circuits, of which the following is a specification.

My invention relates to electric controllers of that type in which the flow of current in one or more electric circuits is controlled by a series of magnetically-operated switches. More particularly it relates to controllers for starting motors and make use of the current traversing the controlled circuit for controlling the operation of the several switches.

One object of my invention is to eliminate the shunt windings used in the operating coils of the usual type of magnetically-operated switch together with the complicated control systems connected therewith.

Another object of my invention is to provide a self-contained switch which will refuse to close its contacts so long as the current flowing through its actuating winding is too high, or above a predetermined value.

Another object is to provide a switch on which it is not necessary to use a magnetic blow-out with the details attendant thereto, and to provide a switch which is cheap to construct.

Referring to the accompanying drawings, Figure 1 is a side elevation of my switch, parts being in section; Fig. 2, an end elevation thereof; Fig. 3, a view showing in elevation and section a second form of construction; Fig. 4, a view showing in side elevation and vertical section a third form of construction; Fig. 5, an end elevation of Fig. 4; Fig. 6, a diagram of current values for operation of the switch at different adjustments; Fig. 7, a diagrammatic view showing the manner of wiring the switch so that when the contacts are closed the actuating winding of the magnet will be in series with those contacts; Fig. 8, a wiring diagram of a motor starter; and Fig. 9 a wiring diagram of a modified construction.

Referring first to Figs. 1 and 2, which show only one of the many forms which my switch may assume, S' is an open rectangular frame of magnetic material, such as cast

iron, mounted on an insulating base or support S². At opposite sides of the frame S' are the bosses or magnetic poles S³ and S⁴, one of them (S⁴) being the inner end of the plug S¹⁹ of magnetic material, such as cast iron, threaded in an opening in the frame so as to be adjustable for a purpose to be hereinafter stated.

Between the poles S³ and S⁴ is the body of the plunger or armature S⁵ composed of magnetic material and provided preferably with an extension S²⁰ of preferably smaller cross-section than the said body.

The plug S¹⁹ is provided with an opening in which is the non-magnetic separator S⁶; I find the ordinary soft steel a suitable material of which to construct the plunger S⁵ with its extension S²⁰.

The plunger or armature S⁵ has connected thereto the non-magnetic rod S⁷ pivoted to the contact arm S⁸, which is pivoted to the frame S' at the bearing S⁹. The engagement of the shoulder S¹⁰ on the rod S⁷ with the top of the frame limits the movement of plunger S⁵ toward the pole S⁴.

The annular winding S¹¹ surrounds preferably the pole S⁴ and the plunger S⁵ at the place where its cross-section changes, which is at the junction of its extension S²⁰ with the body. The body of the plunger S⁵ is shorter than the distance between the poles S³ and S⁴ so that it may have reciprocatory movement between the same under the influence of the winding S¹¹.

The gap S¹² between the plunger S⁵ and the pole S³, I will call the operating gap, and the gap S¹³ between the plunger body and the pole S⁴, I will designate as the lock-out gap. I have found that, by the construction hereinabove described or its equivalent, if the winding S¹¹ is energized beyond a definite value, the weight of the plunger and the parts movably connected thereto together with the magnetic pull in the gap S¹³, that is, between the plunger S⁵ and the pole S⁴ is greater than the pull in the opposite direction in the gap S¹², that is, between the plunger and the pole S³, thereby causing the plunger to remain in its original position, as shown on Fig. 1. I have also found that when the excitation of the winding S¹¹ is diminished to the said value, the magnetic pull on the plunger will predominate

in the gap S^{12} , causing the plunger to move toward the pole S^3 and the arm S^6 to make contact with the brush S^{14} . After the switch has been closed as described, the gap S^{12} has been reduced so that the plunger S^6 will hold the switch closed with a very small amount of excitation in the winding S^{11} . By screwing the plug S^{10} one way or the other and, consequently, changing the relative sizes of the two gaps S^{12} and S^{13} , the point in the excitation of the winding S^{11} at which the plunger operates to close the switch can be varied between wide ranges. I do not limit myself to making the pole S^4 only adjustable.

I have observed that in the construction of the switch shown in Fig. 1 the magnetic flux appears to flow in a divided path in a part of the magnetic circuit, when the winding S^{11} is energized. The magnetic flux may be regarded as flowing from a point in the frame, such as the pole S^3 , across the gap S^{12} into the armature S^5 . Here the flux divides into two paths part flowing through a substantially continuous path including the extension S^{24} and into the plug S^{10} and the frame S' , back to the pole S^3 or the starting point, the other part flowing from the armature S^5 across the gap S^{13} into the pole S^4 and thence through the plug S^{10} and the frame S' to the pole S^3 . The flux flowing across the gap S^{12} produces a force tending to raise the plunger; the flux through the gap S^{13} produces a force tending to prevent the plunger from being raised. If the winding is excited at a low value the larger part of the flux produced thereby will flow through the extension S^{24} and since it passes horizontally into the frame S' , there is no tendency to prevent the plunger from moving upward, only a small part of the flux passing across the gap S^{13} . If the winding is excited at a high value the restricted area in the magnetic circuit at the extension S^{24} forces more flux to pass into the pole S^4 across the gap S^{13} , thereby increasing the force tending to prevent the upward movement of the plunger. I do not restrict myself to the precise construction shown for producing parallel or divided paths for the magnetic flux, nor do I restrict myself to any definite location of the same, since the structure and location of the parts may be changed without departing from the principles of my invention.

I do not limit myself to any theory of the operation of my switch. In its action it appears that when the winding S^{11} is excited too highly, the magnetic pull on the plunger is greater at the gap S^{13} than at the gap S^{12} ; but that, as the excitation of the winding diminishes, the magnetic pull in the gap S^{13} decreases faster than in the gap S^{12} , so that, when the excitation has decreased to a certain value, the pull in the gap S^{12} will predominate.

I have found it desirable to make the opposing surfaces on the opposite sides of the gap S^{12} of different areas. In Fig. 1 I have shown the area of the pole S^3 larger than the upper face of the plunger S^6 , and in Fig. 3 I have shown it smaller, as at S^{15} .

The terminals of the switch are shown at S^{16} and S^{17} , and the terminals of the winding are shown at S^{18} and S^{19} .

Referring now to Figs. 4 and 5 which bear the same reference characters as corresponding parts in Figs. 1 and 2, except that small letters are used instead of capitals, the frame s' is shown to be U-shaped and the winding s^{11} is held in place by the screws s^{21} . The winding s^{11} is wound on the tube s^{22} which extends up to a point near the top of the frame and constitutes a dust-shield.

The tubular separator s^4 is secured to the extension s^{20} so as to travel therewith. The rod s^7 is made preferably of non-magnetic material. The plug s^{10} is prevented from accidental movement by the jam-nut s^{23} . The operation of the apparatus shown in Figs. 4 and 5 is substantially the same as that described for Figs. 1 and 2 and will be readily understood therefrom.

My invention is applicable both to direct and alternating current circuits, but in alternating current circuits the operation of my apparatus depends on the ampere turns in the energizing windings, and not on the frequencies of alternation.

In Fig. 6 I show two curves X and Y, respectively, indicating the values of current in the winding S^{11} , at which the switch will operate, and at which it will lock open at different adjustments of the air gap S^{13} .

The ordinates of the curves represent amperes in the winding of a certain size wire and number of turns. The abscissæ represent the length of the air gap S^{13} in inches. The curve X shows that the switch will operate on 8 amperes flowing in the winding at any adjustment of the air gap from .2 to .7. The curve Y shows that if the air gap S^{13} is, say .3, the value of current above which the switch will lock open is 25 amperes and that it will operate when the current lowers to a point below 25 amperes. It is thus seen that by varying the air gap, S^{13} the value of current at which the switch will lock open will vary.

Referring to Fig. 7, it will be seen that the switch S' is actuated by current flowing from the positive through the resistance R' and the winding S^{11} of the switch to the negative, but that as soon as the contacts of the switch close, the current flows from the positive through the switch contacts and the winding S^{11} to the negative, thereby short-circuiting the resistance R' and placing the switch contacts in series with the actuating winding S^{11} .

Fig. 8 shows a wiring diagram for a motor

starter in which I have shown my switches employed to successively cut out sections of resistance from the motor circuit. The motor is shown with armature A and series field F. Upon closure of the switch S the motor circuit is established from the positive main P through the switch S, the winding s' , the sections R', R², and R³ of resistance, and the armature A and the field F of the motor to the negative main N. If the current in this circuit just established is above the limit at which the switch S^a is set to operate, the switch S^a will not close immediately, but will remain open until the motor speed increases, thus decreasing the current to the limit just mentioned. The switch S^a will then close, short-circuiting the resistance section R', and establish a circuit including its own winding s' together with the winding s^2 of the switch S^b, the resistance sections R² and R³, and the motor armature and field. This will increase the current in the motor circuit, and if this current is above the limit at which the switch S^b is set to operate, the latter will remain open until the motor has again increased its speed and reduced the current to that limit. The switch S^b will then close, short-circuiting the resistance section R², and include the winding s^3 of the switch S^c in the motor circuit. Likewise the switch S^c will remain open until the motor current has again decreased to the limit at which it is set to operate, when it will close its contacts, short-circuiting the remaining section R³ of the resistance, and connect the motor across the line with only the operating windings s' , s^2 , and s^3 of the switches in series therewith.

By connecting a shunt resistance around the windings, as shown at K for the winding s^3 of the switch S^c, the windings may be made to take a part only of the motor current.

The switches will now remain closed until the motor circuit is opened at the switch S, at which all the arc of breaking the circuit is taken, there being no arc found at the contacts of the switches S^a, S^b, and S^c.

In Fig. 9 I have shown a different arrangement of starting resistance, the sections R^a, R^b, and R^c being connected in parallel and finally short-circuited. I have also shown the main switch B in the form of the ordinary magnetic switch, having a shunt winding b, and controlled by the hand switch H. The motor has the armature A and the shunt field f. When the hand switch H is closed, the winding b is energized, causing the switch B immediately to close and a circuit to exist through the field winding f. At the same time a circuit is established from the main P through the switch B, the winding s' , the resistance section R^a, and the armature A to the negative main N. It

the armature current is not above a predetermined value, or when it has diminished to that value, the switch S^a closes connecting the resistance section R^b in parallel with the section R^a, and including the winding s^2 of the switch S^b in the branch containing the resistance section R^b. In a similar manner the switch S^b closes, connecting the resistance section R^c in parallel with the sections R^a and R^b, and including the winding of the switch S^c in the branch containing the section R^c. The armature current again diminishes and the switch S^c closes a circuit through its own winding, short-circuiting all of the resistance sections R^a, R^b, and R^c, as well as the windings of the switches S^a and S^b. These switches, therefore, fall open. The motor-circuit through the armature is then from the main P through the contacts of the switch B, the contacts of the switch S^c, the winding of the switch S^c and the motor armature A to the other main N. When the hand switch H is opened, the switch B opens, taking all of the arc of rupturing the circuit, whereupon the switch S^c opens.

If desirable each switch can be set to close when the motor current is at a different value so that any acceleration of the motor speed can be secured to suit any condition of load.

For simplicity I have shown my invention in connection only with the control of non-reversing motors, but it is clear to those skilled in the art that the principle of my invention may be applied as well to reversing motors or other dynamo electric machines, or to the control of any circuit over which passes a variable current to be controlled.

It is thus seen that I have provided a system of control by which several separately actuated switches may be made to automatically progress to cut out the resistance in a circuit, the progression of the switches being at all times under the control of the circuit itself, all of which is accomplished without the use of shunt windings on the switches, auxiliary contacts, or relays. By the use of a simple winding of coarse conductor on each switch, three functions are performed; namely, the winding furnishes the magnetization for operating the switch; it produces a force delaying the operation until the excitation of the winding is at its proper value; and it holds the switch in its operated position until a very small current passes through its contacts.

In one aspect of the case, the armature portions may be regarded as a part of the switch member.

This application is a continuation of my application Serial Number 583,000, filed September 21, 1910, and my application Serial Number 604,331, filed January 24, 1911.

In some of the appended claims a struc-

ture is described in which flux may be set up by current in the controlled circuit however supplied to the structure, irrespective of the number of coils through which current 5 passes.

With respect to some of the appended claims, it is immaterial what means may be employed to carry out the other functions of the structure, so long as the particular 10 functions described in such claims are effected by flux set up by current in the controlled circuit.

I claim:

1. A controlling device for electric circuits comprising a switch member biased to open position, electromagnetic means energized by current in the circuit to produce two magnetic forces, one for moving the switch member to closed position, and the 20 other for holding it in open position, said forces varying at different rates as the current in said circuit varies.

2. A controlling device for electric circuits comprising a switch member biased to 25 open position, electromagnetic means energized by current in the circuit which reinforces the bias sufficiently to prevent the switch from closing when the energizing current is relatively high but overcomes the 30 bias when the energizing current is low.

3. A circuit to be controlled, a switch member normally biased to open position controlling the circuit, and means controlled by the current in said circuit acting magnetically upon the switch member to reinforce the bias and hold the switch member in open position when the current is relatively high but causing the switch member to move to closed position when the current 40 drops to a predetermined value.

4. A circuit to be controlled, a switch controlling the circuit, a magnetic path in which flux is set up by current in the circuit for holding the switch member from operating 45 to close the switch when the current is high, but permitting the switch member to close the switch when the current is low, and a magnetic path in which flux is set up by current in the circuit for closing the switch.

5. A circuit to be controlled, a switch including a switch member controlling the circuit, a magnetic path in which flux is set up by current in the circuit to hold the switch member from operating to close the switch 55 when the current is relatively high, and a magnetic path in which flux is set up by current in the circuit to close the switch when the current is relatively low and to hold the switch member closed.

6. A circuit to be controlled, a switch including a switch member controlling the circuit, a magnetic path in which flux is set up by current in the circuit to hold the switch member from operating to close the

switch when the current is relatively high, 65 and a magnetic path in which flux is set up by current in the circuit to close the switch when the current is relatively low and to hold the switch member closed, said fluxes varying at different rates as the current in 70 the said circuit varies.

7. A switch, a magnetic structure, means for magnetizing the same, and means whereby, when a portion of the magnetic structure is magnetized beyond a certain value, the 75 switch is prevented from closing and when magnetized at a lower value the switch is magnetically closed.

8. A switch, a magnetic structure for closing the switch, having a portion of limited 80 magnetic capacity, means for magnetizing the same, and means preventing the switch from closing when the said capacity is exceeded.

9. In a motor starter, the combination 85 with the armature circuit, of a resistance included therein, a switch member, electromagnetic means connected with said circuit for positively moving said switch member to short circuit said resistance and acting directly upon the switch member itself for holding said member against moving so long as the current in said circuit exceeds a predetermined amount.

10. An electromagnetic switch comprising 95 a single energizing winding, a pair of contacts normally in open position and caused to be closed by the energization of said winding, and a magnetic structure acted upon by the said winding to prevent 100 the closure of the contacts when the winding is energized above a predetermined value.

11. An electromagnetic switch comprising 105 a movable contact and a fixed contact normally out of engagement with each other, a single magnetizing winding, a magnetic structure which when energized above a predetermined value by said winding causes two opposing forces to be exerted 110 upon the movable contact, one tending to move it into engagement with the fixed contact and the other holding it out of engagement therewith, and means whereby the holding out force is overcome by the 115 closing force when the energizing current falls to a relatively low value so as to cause the movable contact to move into engagement with the fixed contact and be held firmly in contact therewith by said closing 120 force.

12. An electromagnetic switch comprising 125 a movable switch member, an electromagnet arranged to exert two forces thereon one tending to hold the switch member in open position and the other tending to close it, and a magnetic member of limited magnetic carrying capacity arranged to short

- circuit the former magnetic force at low excitation so as to cause the latter magnetic force to prevail.
13. A controlling device for electric circuits comprising a switch member having two armature portions, an electromagnet co-operating with one of said armature portions to close the switch and with the other armature portion to hold it open, and magnetic shunting means arranged to cause the flux of said magnet to attract the holding armature portion upon a rush of current above a predetermined value and release it so as to cause the switch to close when the current falls to said value.
14. A controlling device for electric circuits comprising an electromagnet having two pole pieces, a pivoted switch member having an armature portion co-operating with each of said pole pieces and normally in open position with one armature portion resting adjacent one pole piece but separated therefrom by an air gap, a magnetic member which becomes saturated when the current in said magnet is high arranged to shunt said air gap so as to cause the flux of the magnet to cross the gap and hold the switch open when the current is high and release it when the current falls to a predetermined value so that it will be closed by the other armature portion.
15. An electric switch comprising an electromagnet, switch contacts closable thereby, and magnetic means for holding said contacts in open-circuited position during the passage through the magnet of a current above a predetermined value and for moving said contacts to closed-circuited position when the current through said magnet becomes of the predetermined value.
16. In a switch, a magnetic circuit including a movable mechanism, and a winding for producing magnetic pulls on said mechanism at two places, said magnetic circuit having parallel paths, one path including a gap, for causing the pulls to vary differently at the two places when the ampere turns in the winding are varied, and means for changing at will the relation between said pulls.
17. In a switch, a magnetic circuit including a movable member, there being air gaps in said circuit adjacent to said movable member, an energizing winding for producing opposing magnetic pulls on said movable member one or the other of which pulls may preponderate, the pull on the movable member in the direction tending to prevent the actuation of the movable member increasing faster than that in the other direction when the current strength in the winding is increased.
18. A magnetic circuit including a movable member, a gap at either end of said member, and a winding for simultaneously producing, in accordance with variations of ampere turns therein, a varying magnetic pull on each end of said member, the pull on the end tending to prevent movement of the movable member increasing faster than the pull on the other end when the ampere turns in the winding are increased.
19. A magnetic circuit including a movable member, a gap at either end of said member, and a winding for simultaneously producing, in accordance with variations of ampere turns therein, a varying magnetic pull on each end of said member, the pull on one end varying differently from the pull on the other end, and means for changing at will the relation between the pulls.
20. A magnetic circuit, an armature movable with respect to two poles thereof, a winding therefor, there being a reluctance in said circuit having a magnetic shunt so that an excitation in the winding of a higher than a predetermined value prevents movement of the armature and a lower excitation therein causes the movement of the armature toward one of the poles against a restraining force.
21. In an electromagnet switch, an energizing winding, and a magnetic circuit including a movable mechanism, said circuit having a portion of high reluctance shunted by a portion of lower reluctance so that the movable mechanism is magnetically held in one position if the current in the winding is above a predetermined value, and the movable mechanism is caused to be moved by magnetic force to another position when the current becomes smaller.
22. In a magnetically operated device, a movable mechanism, a magnetizing winding which when energized sets up two forces with respect to said movable mechanism, one actuating force tending to move the movable mechanism, and the other an opposing force tending to prevent the same, the opposing force decreasing more rapidly than the actuating force as the ampere turns in the winding decrease.
23. In a switch, a magnetic circuit including a stationary portion and a movable portion, switch contacts controlled by the said movable portion, there being air gaps at two places between said stationary portion and said movable portion, one of said air gaps being shunted by a shunting member of magnetic material, said shunting member being of less cross section than the average cross-section of said magnetic circuit, and means for setting up a magnetic flux in said circuit.
24. In a switch, a magnetic circuit including a stationary portion and a movable portion, a winding for producing magnetic pulls on said movable portion at two places,

the magnetic flux set up by said winding passing from the stationary portion to the movable portion through an air gap to produce a pull at one of said places and passing through an air gap and a restricted part of the magnetic circuit in parallel relation thereto to produce a magnetic pull at the second of said places, whereby the magnetic pulls on said movable portion of the magnetic circuit at said two places are caused to vary differently when the ampere turns in the winding are varied, the winding being in series with the contacts when closed.

25. In a switch, a magnetic circuit including a stationary portion and a movable portion, a winding for producing magnetic pulls on said movable portion at two places, the magnetic flux set up by said winding passing from the stationary portion to the movable portion through an air gap to produce a pull at one of said places and passing through an air gap and a restricted part of the magnetic circuit in parallel relation thereto to produce a magnetic pull at the second of said places, whereby the magnetic pulls on said movable portion of the magnetic circuit at said two places are caused to vary differently when the ampere turns in the winding are varied, and means for changing at will the relation between the pulls at said two places.

26. In a switch, a magnetic circuit including a stationary portion and a movable portion, a winding for producing magnetic pulls on said movable portion at two places, the magnetic flux set up by said winding passing from the stationary portion to the movable portion through an air gap to produce a pull at one of said places and passing through an air gap and a restricted part of the magnetic circuit in parallel relation thereto to produce a magnetic pull at the second of said places, whereby the magnetic pulls on said movable portion of the magnetic circuit at said two places are caused to vary differently when the ampere turns in the winding are varied, and means for adjusting the air gaps at the two places relative to each other.

50. 27. In a switch, a magnetic circuit having movable and stationary portions, two places on said movable portion adapted to be attracted toward said stationary portion, a winding which when energized at one value causes the attraction at one place to hold the said switch in the position it assumes when the winding is deenergized, and means including a magnetic shunt for causing said winding, when the ampere turns therein are reduced, to cause the attraction at the other place to move the movable portion to its operated position.

28. A magnetic circuit including a movable member, said circuit containing an op-

erating gap and a lockout gap, the operating gap being greatest when the movable member is in its normal unoperated position, a magnetic shunt for lockout gap, and a winding, which when energized at a certain value causes the movable member to remain in its unoperated position, and when the ampere turns in said winding are reduced causes the closure of the operating gap and the operation of the switch.

29. In a switch, a magnetic circuit having an operating gap normally open and a lockout gap which increases when the operating gap decreases, a winding for operating said switch, and means including a magnetic shunt around the lockout gap which causes the winding to hold the switch in its unoperated position when energized with a certain number of ampere turns, and causes the winding to close the operating gap and operate the switch when the ampere turns are reduced.

30. In an electromagnetic device, a movable element, a winding for moving said element from its initial position, and a magnetic structure acted upon by said winding to prevent the movement of said element from said initial position when the winding is energized above a predetermined value.

31. In a switch, a movable element, an operating winding therefor, a pair of contacts connected in the circuit of said winding and closable by said movable element, and a magnetic structure acted upon by said winding to prevent the operation of said element when the winding is energized above a certain value.

32. A controlling device for electric circuits comprising a switch member, an electromagnet for moving said member to closed position, and a magnetic shunt arranged to cause the flux of said magnet to hold the switch open when the current in the magnet is high and release it when the current falls to a predetermined value.

33. A controlling device for electric circuits comprising a switch member, an electromagnet for moving said member to closed position, a magnetic shunt arranged to cause the flux of said magnet to hold the switch open when the current is high until it falls to a predetermined value, and means for causing the magnet to hold the switch from closing when the current passes through said predetermined value in rising to the higher value.

34. A controlling device for electric circuits comprising a movable switch member normally in open position having two armature portions, an electromagnet co-operating with one of said portions to close the switch, said second armature portion resting normally adjacent a pole piece of said magnet but separated therefrom by an air gap, and

5 a magnetic member arranged to shunt said air gap to cause second armature portion to be held upon a rush of current above a predetermined value and to be released when the current falls to said value.

10 35. A controlling device for electric circuits comprising a switch operating member having two armature portions, an electromagnet coöperating with one of said armature portions to close the switch and with the other armature portion to hold it open, and means whereby the flux of said magnet is caused to attract one armature portion when the current in the magnet is relatively 15 high and when the current falls to a predetermined value release it and cause it to be closed by the other armature portion.

20 36. In a magnetically-operated device, a magnetic circuit having a plurality of arms, an energizing winding surrounding one arm 25 of said circuit, said arm being composed of three members, one of which is movable and located between the other two, the magnetic flux in said movable member tending to move it toward one fixed member or the other depending upon the ampere turns in said winding.

30 37. In a magnetically-operated device, a magnetic circuit divided into two branches of different reluctance, a movable member in the circuit and an energizing winding for said circuit surrounding said movable member where the magnetic circuit divides.

35 38. In a switch, a branched magnetic circuit having two gaps, an energizing winding therefor, and a movable mechanism a portion of which carries the entire flux, and another portion only a part thereof, the movement of the movable mechanism increasing one gap and decreasing the other, and the second portion carrying substantially all the flux at one value of current in the energizing winding.

40 39. In a switch, a magnetic circuit having a stationary portion and a movable mechanism, switch contacts caused to close by the said mechanism, a magnetizing winding for said magnetic circuit, substantially all of the magnetic flux set up in said stationary portion of said magnetic circuit by said magnetizing winding entering said movable mechanism through a gap, a portion of the magnetic flux in said movable mechanism leaving said movable mechanism through a second gap, there being a magnetic path or shunt around the second gap.

45 40. In a switch, a magnetic circuit having a stationary portion and a movable mechanism, a magnetizing winding for said magnetic circuit, substantially all of the magnetic flux set up in said stationary portion of said magnetic circuit by the magnetizing winding entering the movable mechanism through a gap, a portion of the magnetic

50 flux in said movable mechanism leaving the movable mechanism through a second gap, there being a magnetic path or shunt around the second gap, and means for varying the proportion of the magnetic flux which passes through the second gap.

55 41. In a magnetically-operated device, a magnetic circuit, an energizing winding therefor, and a movable mechanism actuated thereby, one portion of the magnetic circuit being divided into a gap branch and a contracted branch to cause magnetic flux produced by a high excitation of the winding to pass through the gap, the force produced thereby tending to prevent the movement of the said mechanism.

60 42. In a switch, a movable core for actuating said switch, a magnetizing winding surrounding said core, a return magnetic circuit external to said winding, an air gap between one end of said core and a part of said return magnetic circuit, a portion of the other end of the core being reduced in cross-section and forming a shoulder with the body of the core, said reduced part of the core extending into a part of the return magnetic circuit and being surrounded by a sleeve of magnetic material, one end of said sleeve being adjustable toward or away from the shoulder on said core.

65 43. In a switch, a movable core adapted to actuate said switch, a magnetizing winding surrounding said core, a return magnetic circuit for said winding, an air gap between one part of said core and a part of said return magnetic circuit, a portion of the core 100 toward its other end being of less cross-section than the body of the core and extending into a portion of said return magnetic circuit, and a sleeve of magnetic material surrounding the portion of the core of 105 reduced cross-section, said sleeve being adjustable in a direction parallel to the axis of said core.

70 44. A controlling device for electric circuits comprising a movable switch member, an electromagnet coöperating therewith to either close the switch or hold it open, said magnet being provided with a permanent metallic path for its flux which becomes saturated when the current in the magnet is 110 relatively high and causes the flux to take a path which holds the switch open and when the current falls to a predetermined value releases the switch so that it will be closed by the magnet.

75 45. A switch for electric circuits comprising stationary and movable contact members, an actuating coil and means rendered effective for closing the switch only when the actuating coil is energized within predetermined limits.

80 46. A switch for electric circuits comprising stationary and movable contact

members, an actuating coil and means rendered effective for closing the switch only when the actuating coil is supplied with current within predetermined limits.

5 47. An electromagnetic switch comprising a movable switch member, an electromagnet arranged to exert two forces thereon, one tending to hold the switch member in open position and the other tending to move it to closed position, and means for causing the former force to prevail at high excitation and the latter at low excitation.

10 48. A controlling device for electric circuits comprising a movable switch member, an electromagnet coöperating therewith to either close the switch or hold it open, said magnet being provided with a permanent metallic path for its flux which becomes saturated upon a rush of current above a predetermined value and causes the flux to take a path which holds the switch open and releases the switch so that it will be closed by the magnet when the current falls to said value, and means for preventing the magnet from releasing the switch member when the current passes through the predetermined value in rising to the higher value.

15 49. A controlling device for electric circuits comprising a switch member; an electromagnet for operating the same comprising a magnetizing winding and a branched magnetic circuit coöperating therewith, and means for varying the rate of change of flux in said branches as the current in said

20 50. A controlling device for electric circuits comprising a switch member biased to open position, an energizing winding arranged to exert two forces thereon one of which reinforces the bias sufficiently to prevent the switch from closing when the energizing current is relatively high while the other force overcomes the bias when the energizing current is lower.

25 51. An electromagnet comprising a stationary core member and a movable core member having a normal flux path that tends to produce relative movement between them and a leakage or abnormal flux path that tends to prevent relative movement between them when energized.

30 52. A magnet switch comprising a stationary core member, a coil therefor and a movable core member providing normal and leakage flux paths of unequal reluctance, the magnetic flux traversing the normal flux path tending to produce a relative movement between the core members and the magnetic flux traversing the leakage flux path opposing relative movement of the members.

35 53. An electromagnet comprising stationary members and a relatively movable magnetizable core member and an energizing

coil, the directional tendency of movement of the movable member being dependent upon the intensity of the flux produced by the coil in the said members.

40 54. The combination of a circuit to be controlled, and a series of electromagnetic switches therefor, adapted to operate in a predetermined order, the operating coil of each of certain switches being brought into the said circuit by the closure of a preceding switch and delaying the operation of the switch which it controls.

45 55. The combination of a circuit to be controlled, and a series of electromagnetic switches therefor, adapted to operate in a predetermined order, the operating coil of each of certain switches being brought into the said circuit by the closure of a preceding switch and holding open and later closing the switch it controls.

50 56. The combination of a circuit to be controlled, and a series of electromagnetic switches therefor, adapted to operate in a predetermined order, the operating coil of each of certain switches being brought into the said circuit by the closure of a preceding switch and delaying the operation of the switch which it controls and later holding the said switch in its operated position.

55 57. The combination of a circuit to be controlled, and a series of electromagnetic switches therefor, adapted to operate in a predetermined order, the operating coil of each of certain switches being brought into the said circuit by the closure of a preceding switch and delaying the operation of the switch which it controls when the current in the circuit is above a certain value.

60 58. The combination of a circuit to be controlled, a series of electromagnetic switches therefor, adapted to operate in a predetermined order, the operating coil of each of certain switches being normally deenergized and brought into said circuit by the closure of a preceding switch and delaying the operation of the switch which it controls, and connections for including each coil in series with the switch it controls when it operates.

65 59. The combination of a circuit to be controlled, a series of electromagnetic switches therefor, adapted to operate in a predetermined order, the operating coil of each of certain switches being brought into the said circuit by the closure of a preceding switch and delaying the operation of the switch which it controls and connections whereby, after all the switches have been operated, only the final switch in the series is held in its operated position.

70 60. The combination of a motor, a circuit therefor, resistance in the circuit, a series of electromagnetic switches for controlling the resistance, adapted to operate in a predetermined order, the operating coil of each

of certain switches being brought into the said circuit by the closure of a preceding switch and delaying the operation of the switch which it controls and later holding it closed.

61. The combination of an electric motor, a circuit therefor, banks of resistance in the circuit for controlling the motor, and a series of electromagnetic switches adapted to op-

erate in a predetermined order, each controlling one bank of resistance, the operating coil of each of certain switches being brought into the said circuit by the closure of a preceding switch and delaying the operation of the switch which it controls.

Signed at Cleveland, Ohio, this 4th day of February, 1920.

HARRY R. CANFIELD.
